UNITED STATES PATENT OFFICE.

PIETRO SCARDINO, OF NEW YORK, N. Y.

PAPER-TRIMMING APPARATUS FOR PAPER-HANGERS' USE.

1,099,942.

Specification of Letters Patent.

Patented June 16, 1914.

Application filed February 21, 1914. Serial No. 820,146.

To all whom it may concern:

Be it known that I, PIETRO SCARDINO, a subject of the King of Italy, residing in the borough of Brooklyn, county of Kings, city 5 and State of New York, have invented certain new and useful Improvements in Paper-Trimming Apparatus for Paper-Hangers' Use, of which the following is a full, clear, and exact description.

10 This invention relates to straight-edges for paper-hangers' trimming tables, and its chief object is to provide an improved device which is mechanically held in operative position during the trimming operation but 15 can be swung up and held out of the way when the user is adjusting the paper.

To this and other ends the invention consists in the novel features of construction and combinations of elements hereinafter 20 described.

One form of the invention is illustrated in the accompanying drawings, in which—

Figure 1 is a plan view of a portion of a table equipped with my improved straight-edge or trimming guide. Fig. 2 is a front view, and Fig. 3 is an end view, of the same. Fig. 4 is a detail sectional view on line 4—4 of Fig. 1. Fig. 5 is a detail sectional view on line 5—5 of Fig. 1.

30 The straight-edge 10 is arranged at the front of the table 11, and its ends are fitted between the inwardly extending arms 12, 13, of the transverse end-brackets or supports 14, 15, in which they are bound securely by means of binding bolts 16, 17, and wing-nuts 18, 19. The brackets 14, 15, extend forwardly from the straight-edge and at their front ends are provided with pivot-pins 20, 21, extending into suitable openings 35 in the end-edges of the table. At their rear ends the brackets are turned upwardly, the arms 12, 13, being formed on the upwardly extending portions, as shown. To permit easy removal of the straight-edge, its ends 40 are slotted, as at 22, 23, to receive the bolts 16, 17. Hence, to release the straight edge it is only necessary to loosen the wing-nuts 18, 19, whereupon the brackets 14, 15 can be pulled off endwise, the pivot-pins 20, 21 45 coming out of their sockets in the table.

From the foregoing it will be seen that when the workman desires to adjust the paper for trimming he swings the straight-edge upwardly on the pivots, as in dotted 50 lines in Fig. 3, after which the paper can

be readily adjusted and the straight-edge then swung down upon the paper, ready for the trimming, which may of course be performed by a knife, or a wheel-cutter not shown. If desired the straight-edge may be 60 equipped with a handle 24, for example, on its rear edge. To hold the straight-edge in raised position a prop 25 may be provided, pivoted at the rear edge of the straight-edge to a depending finger 26 on a rearward extension 27 on the arm 12 of bracket 14. The dotted lines in Fig. 3 show the prop in use.

Inasmuch as the trimming position of the straight-edge is fixed, the cut always occurs on the same line and hence would speedily 70 groove the surface of the table, thereby impairing the accuracy of the cut. To obviate this feature the table is provided with a cutting bed under the front of the straight-edge to receive the cut. This bed 75 is preferably a strip of brass 28, fastened to the table in any convenient manner.

It is to be understood that the invention is not limited to the specific construction herein described, but can be embodied in 80 other forms without departure from its proper spirit and scope.

I claim:

1. The combination of a trimming table, transverse brackets pivoted to the table and 85 each having inwardly extending clamping arms, a straight edge having its ends extending between said arms and provided with slots, and binding bolts passing through the arms and the slots. 90

2. The combination of a trimming table having pivot-holes in its end-edges adjacent to its front edge, brackets 14, 15, extending rearward from said holes and having pivot pins 20, 21, extending into said holes, upper 95 and lower clamping arms 12, 13, carried by the brackets at their rear ends and overlying the table, a straight edge having its ends embraced by said arms and provided with openings between said arms, and releasable 100 bolts 16, 17, extending through the arms and the openings to clamp the arms removably on the ends of the straight edge and hold the brackets in pivotal connection with the table. 105

3. The combination of a table, a rearwardly extending bracket 14 pivoted to an end-edge of the table at the front thereof, upper and lower clamping arms 12, 13 carried by the bracket and overlying the table, 110

a straight edge having an end fitted between the said arms, means for releasably binding the straight-edge between the arms, an extension 27 extending rearwardly from the 5 upper arm 12 and having a depending finger 26 in rear of the straight edge, and a prop 25 pivoted at one end to said finger.

In testimony whereof I affix my signature in the presence of two subscribing witnesses.

PIETRO SCARDINO.
